UNITED STATES PATENT OFFICE.

ERNST F. SODERQUIST AND FRANK A. MCADAMS, OF HARTFORD,
CONNECTICUT.

ANTIREFILLABLE BOTTLE.

SPECIFICATION forming part of Letters Patent No. 600,560, dated March 15, 1898.

Application filed July 14, 1897. Serial No. 644,505. (No model.)

To all whom it may concern:

Be it known that we, ERNST F. SODERQUIST and FRANK A. MCADAMS, citizens of the United States, residing at Hartford, in the 5 county of Hartford and State of Connecticut, have invented certain new and useful Improvements in Antirefillable Bottles, of which the following is a specification.

This invention relates to antirefillable bottles, the object being to provide a simple and inexpensive device of this character so constructed as to prevent refilling after the original contents have been poured therefrom.

Our improved bottle embodies, essentially, 15 a valve-seat in the neck, a guard fitted in said neck and having at its inner end a concave recess, a valve, and a valve-actuator situated between the valve and said recess.

In the form of the invention represented 20 the guard consists of two sections, one set within the other, one member of the guard having a lug or projection fitting in a corresponding notch in the neck of the bottle, and a spreader is preferably furnished to force 25 said lug or projection into the notch when the guard is inserted in place into the neck after the bottle is filled.

In the drawings accompanying and forming 30 part of this specification, Figure 1 is a longitudinal central sectional view of the upper part of our improved bottle. Fig. 2 is a similar view of the neck, showing the position taken by the valve and its actuator when the bottle is tilted to pour therefrom. Fig. 3 is 35 a similar view showing the neck in a substantially horizontal position and the valve as closed. Figs. 4 and 5 are transverse sectional views taken, respectively, in the lines 4 and 5, Fig. 1; and Figs. 6 and 7 are detail 40 views, in side elevation, of the two sections of the valve-guard.

Similar characters designate like parts in all the figures of the drawings.

In Fig. 1 of the accompanying drawings a 45 portion of a bottle of ordinary construction is shown, the valve being preferably situated in the neck thereof. The body is designated by B, and the neck by N. The valve may be of any suitable type adapted to close the port 50 2 in the neck. The valve in the present case is designated by V, and it consists of a sphere

or ball of suitable material, such as rubber or glass, resting on the seat 3, and when the bottle is in a vertical or substantially horizontal position, as shown, respectively, in Figs. 55 1 and 3, the valve is adapted to cover the port 2. When the bottle is tilted to pour therefrom, as indicated in Fig. 2, the valve will roll away from or uncover the port 2, so as to permit the liquid to pass through said port 60 and the neck of the bottle. The wall of the valve-chamber 4 is fluted or grooved, as at 5, so that when the valve is moved away from its seat, as indicated in Fig. 4, the liquid can freely flow under the valve through the 65 grooves 5.

In connection with the valve V an actuator, such as A, is provided, adapted positively to force said valve against its seat 3 to cover the port 2 when the bottle is returned to an 70 upright position after any part of the contents have been emptied therefrom.

The actuator A is a self-operative or gravity actuator, it consisting in the present instance of a sphere or ball heavier than the 75 valve, and it is effective when the bottle is in certain positions to move the valve against its seat for covering the port 2, whereby the fraudulent refilling of the bottle can be prevented.

In conjunction with the valve and its actuator a guard or plug, such as G, is provided, having a concavity or conical recess 6 at its inner end.

The concavity or conical recess 6 at the inner end of the guard or plug G forms a pocket to receive the actuator or ball A when the bottle is tilted, whereby the valve V can move away from its seat a sufficient distance to uncover the port 2, as indicated in Fig. 2.

The plug or guard G, which is tightly locked within the neck N, consists of two sections 7 and 8, the smaller section 8 loosely fitting within the socket 7' in the larger section 7, as represented in Figs. 1, 2, and 3. The inner end of the plug has a series of longitudinal grooves or channels 9, which communicate with the transverse or annular channel or groove 10, formed in the plug-sections 7 and 8, respectively, as shown in Fig. 1. A second 95 series of longitudinal grooves 12 is formed in the two plug-sections, and said grooves also 100

communicate with the transverse channel 10. The outer end of the plug is recessed at 13, and the wall of said recess is provided with a plurality of ports or openings 14.

- 5 When the bottle is inclined, as indicated in Fig. 2, the liquid will flow through the port 2, and from thence along the channels 9, 10, and 12, and then will pass through the ports 14 into a suitable receptacle. The outer end of 10 the guard or plug G is furnished with an annular flange 15, fitting against the shoulder 16 on the inside of the neck N of the bottle, said shoulder preventing the guard from being forced too far into said neck.
- 15 One of the sections of the plug or guard, as the part 8 thereof, is furnished with a locking lug or projection, as 17, adapted to enter a corresponding recess 18 in the neck of the bottle, a suitable spreader being preferably 20 furnished to force the lug into the recess to hold the plug in place.

The spreader for the plug is designated by S, and it consists of a rubber or other spring whose opposite ends are inserted into the 25 sockets 19 and 20, formed in the respective plug-sections.

The bottle having been filled to the proper height, the valve is inserted into the neck N, after which the valve-actuator A is placed in 30 the neck. The two parts of the plug having been assembled and the spreader S being in place, the plug is inserted in the neck until the flange 15 abuts against the shoulder 16, at which time the locking-lug 17 will have 35 reached a point opposite the recess or notch 18, into which it is then forced by the spreader S.

Means are provided to prevent access to the spreader S from the outside, the means in 40 the present case consisting of the tongue or rib 21 on the plug-section 7, fitting within the groove or notch 22 in the plug-section 8, as shown in Figs. 1, 2, and 3, the tongue or rib 21 being of a length slightly exceeding the 45 width or diameter of the spreader S, so that if a knife or other instrument be introduced into the space between the two plug-sections it will strike the tongue or rib 21, which thereby prevents its entrance to the spreader, 50 so that the latter cannot be severed or removed.

In Fig. 1 the bottle is shown in its upright position and the valve V held against its seat 3 and over the port 2 by the gravity-actuator A, 55 so that it is impossible to pour any liquid into the bottle. When the bottle is tilted or inverted to pour, the actuator A will drop into the concavity 6 of the plug, so that the valve V can be moved away from its seat by 60 the pressure of the outflowing liquid to uncover the port 2, whereby the contents or any part thereof can be poured from the bottle.

When the bottle is inverted or approximately so and an attempt is made to introduce a liquid, the latter will by its pressure carry the 65 valve against its seat to cover the port 2.

When the bottle is being returned to its upright position and when it reaches substantially a horizontal line, the spherical actuator A will be caused to roll along the oblique 70 or inclined face of the concavity 6, thereby acting against the valve to close same, so that the bottle cannot be refilled when it is in a horizontal or substantially level position.

Having described our invention, we claim— 75

1. A bottle of the class specified comprehending a neck having a valve-seat; a valve; a plug having a recess in its inner end and constructed in two sections one of which is smaller than the other, the smaller section being 80c loosely fitted in a socket in the larger section and having a locking-lug adapted to enter a corresponding notch in the neck of the bottle, and the larger section being provided with a tongue located to enter a groove in the smaller 85 section; a spreader for the plug-section; and an actuator located in the space between said recess and valve.

2. A bottle of the class specified comprehending a neck having a valve-seat and furnished with an annular shoulder; a valve; an exteriorly-grooved two-part plug having a recess at its inner end and provided with a flange at its opposite end fitting against said annular shoulder, one of the plug-sections 95 having a locking-lug adapted to enter a corresponding notch in the neck of the bottle, and one of them being provided with a tongue for entering a groove on the other section; a spreader seated in sockets formed in the two 100 plug-sections; and a gravitational actuator located in the space between said recess and the valve.

3. A bottle of the class specified comprehending a neck having a valve-seat and furnished with an annular shoulder near its outer end; a valve; a plug constructed in two parts one of which is smaller than, and is loosely fitted in a socket in, the other, one of the sections of the plug having a locking-lug 110 adapted to enter a notch in the neck, the plug being externally grooved, and the larger section having a tongue adapted to enter a groove in the smaller section and also having a flange fitted against said shoulder; an elastic spreader supported in sockets formed in the respective sections of the plug; and a spherical gravitational actuator disposed in the space between said recess and the valve. 115
